Inventor:

Karl Paul Gottschalk

By *General Electric*
his Attorney.

UNITED STATES PATENT OFFICE.

KARL PAUL GOTTSCHALK, OF DRESDEN, GERMANY, ASSIGNOR TO HENRY STAIER,
OF GRUNAU NEAR ROSSWEIN, SAXONY, GERMANY.

APPARATUS FOR ADJUSTING AND FIXING THE SETTING OR STRADDLING OF PARTLY-CUT MATCHES OF PAPER, PASTEBOARD, OR THE LIKE AND STILL CONNECTED IN THE SHAPE OF A CONTINUOUS STRIP OR BAND.

Application filed March 25, 1922. Serial No. 546,945.

To all whom it may concern:

Be it known that I, KARL PAUL GOTTSCHALK, engineer, a subject of the Republic of Saxony, German Republic, and resident 5 of 19 Reickerstrasse, Dresden, Republic of Saxony, German Republic, have invented a new and useful apparatus for adjusting and fixing the setting or straddling of partly-cut matches of paper, pasteboard, or the like 10 and still connected in the shape of a continuous strip or band, of which the following is a specification.

The present invention has for its object 15 an apparatus for adjusting and fixing the setting or straddling of partly cut matches of paper, pasteboard or the like and still connected together in the shape of a continuous strip or band.

The apparatus for adjusting and fixing 20 the setting or straddling mentioned consists in a known manner of two wheels gearing together, so called straddle-wheels, through which the partly cut matches still connected together as an endless band are 25 passed in such a manner that the matches following each other are mutually bent once to the right and once to the left, therefor alternately to both sides, i. e. straddled.

The endless band consisting of the separate 30 matches is, during its longitudinal movement, kept and guided between two delivery-rollers. Now the novelty of the present invention consists in that the mutual distances of the delivery-rollers and the wheels 35 gearing together, the so-called straddle-wheels, can be varied and the matches following each other thus more or less set or straddled to both sides by varying the distances mentioned.

40 A guide-bar of triangular section or otherwise shaped is arranged in rear of the wheels gearing together and serves as a support for the matches set or straddled to both sides of the bar and for fixing the setting or straddling.

45 The object of the present invention is represented on the drawing annexed as an example of construction. Fig. 1 is a side-elevation and a partial section and Fig. 2

a horizontal section according to the line 50 1—2 of Fig. 1.

a is the endless band of the partly cut matches, c^1 , c^2 are the delivery-rollers and b^1 , b^2 the vertically arranged shafts to which the rollers c^1 , c^2 are fastened. The endless 55 band a is guided between the rollers c^1 , c^2 . d^1 , d^2 are setting or straddling wheels fastened to the shafts b^1 , b^2 and gearing together. The distance between the delivery-wheels c^1 , c^2 and the setting or straddling-wheels d^1 , d^2 can suitably be varied and adjusted, for instance by a displacement of the setting or straddling wheels along their shafts, b^1 , b^2 . 60

By the adjustment of this distance the 65 degree of setting or straddling the matches following each other can be controlled so that the setting or straddling will become the larger, the nearer the delivery and setting-wheels are adjusted to each other.

70 e is a guide-bar which serves to ensure the set or straddled position of the matches and is of triangular or any other suitable shape so that the matches straddled to both sides run, so as to speak, onto said guide-bar. In 75 this manner the set or straddled position of the matches is ensured and the set or straddled matches are guided in a uniform height above the dip-disc during the dipping-operation. 80

What I claim is:

1. In an apparatus for adjusting and fixing the setting or straddling of partly cut matches of paper, paste board or the like and still connected together in the shape of an endless strip or band in combination with delivery rollers for moving or supplying the endless band mentioned, of wheels 85 gearing together for passing the band to be set or straddled between their teeth and for alternately bending the partly cut matches to both sides of the band and means for varying and adjusting the setting or straddling. 90

2. In an apparatus for adjusting and fixing the setting or straddling of partly cut matches of paper, pasteboard or the like and still connected together in the shape of 95

an endless stripe or band, in combination with delivery-rollers for moving or supplying the endless band mentioned, of wheels gearing together for passing the band to be set or straddled between their teeth and for alternately bending the partly cut matches to both sides of the band, means for varying and adjusting the setting or straddling, and

a guide-bar arranged in rear of the wheels mentioned for fixing the obtained setting or straddling of the matches. 10

In testimony, that I claim the foregoing as my invention, I have signed my name this 15th day of February, 1922.

KARL PAUL GOTTSCHALK.
